UNITED STATES PATENT OFFICE.

JOHAN WALDEMAR LINDBERG, OF PARIS, FRANCE. ASSIGNOR TO AKTIEBOLAGET EXQVISITA, OF STOCKHOLM, SWEDEN, A SWEDISH COMPANY.

LOCK.

Application filed March 12, 1923. Serial No. 624,330.

To all whom it may concern:

Be it known that I, JOHAN WALDEMAR LINDBERG, a subject of the King of Sweden, residing at Paris, France, have invented a new and useful Improvement in Locks (for which I have filed an application in Sweden May 29, 1920), of which the following is a specification.

The present invention relates to an improvement in self-locking locks provided with beveled latch-bolt and with a bolt-actuating arm or the like which is rotatable in the lock and serves for retracting the latch-hole for opening the lock, and which latch-bolt and bolt-actuating arm are adapted to cooperate in such manner that after the lock has been opened the latch-bolt is retained by said arm in such intermediate position between its maximum extended position and its maximum retracted position that only the bevel of the bolt projects outside the lock casing, and that after the latch-bolt has been pushed from such intermediate position back into the lock casing by cooperation with the door-post or the like it is released from engagement with said bolt-actuating arm and is free to be moved by its spring outwards to its maximum extended or locking position. The invention consists principally in that the latch-bolt and the bolt-actuating arm are so arranged that during the entire movement of the latch-bolt from its maximum retracted position within the lock casing to the said intermediate position, in which only its beveled portion projects outside the lock casing, the said parts, namely, the latch-bolt and the bolt-actuating arm, are in positive engagement with one another for the purpose that after the lock has been opened the latch-bolt shall be securely stopped by the bolt-actuating arm in the said intermediate position. According to a suitable embodiment of the present improvement one of the parts—either the latch-bolt or the bolt-actuating arm—is provided with a projection which is guided in a slot or groove in the other part in such manner that the projection can not become released from said slot or groove until the bolt-actuating arm and the latch-bolt

have arrived in those positions in which only the beveled portion of the bolt projects outside the lock casing.

An embodiment of a lock constructed in accordance with the present invention is illustrated in the accompanying drawing. Fig. 1 shows a side view of the lock, one of the side plates of the lock casing being removed, and the different parts occupying positions corresponding to the latch-bolt being in its maximum extended position, the lock thus being locked. Fig. 2 is a side view showing the parts in the positions occupied when the latch-bolt is fully retracted within the lock casing, the lock thus being opened. Fig. 3 is a similar view showing the parts in the positions occupied when only the beveled portion of the bolt projects outside the lock casing. Fig. 4 shows an edge view of a portion of the lock casing, the catch knob being cut away.

The latch-bolt 1, which is beveled on one side, moves in the usual manner in a corresponding opening in the end plate 2 of the lock casing 3. In the embodiment illustrated the latch-bolt 1 is provided with a rod 4 having a head 5, said rod 4 being placed in recesses provided for the same in flanges or shoulders 6 and 7 on a plate 8 in such manner that the latch-bolt 1 bears against the outer face of the flange 6 and the head 5 bears against the flange 7, as illustrated in the drawing. The latch-bolt 1 and the plate 8 will thus move in unison. The plate 8 is provided with other flanges or projections 9 having apertures traversed by a rod 10 which is inserted through an aperture in one end of the lock casing and into the apertured lugs 11 in the casing, to which lugs 11 said rod 10 is secured in suitable manner. The rod 10 thus forms a guide for the plate 8. Between one of the flanges 9 of the plate 8 and one of the lugs 11 in the casing there is inserted a spring 12 which tends to move the plate 8 outwards and thus to move the latch-bolt 1 out of the casing.

A bolt-actuating arm 13 is rotatably journaled in the casing 3 and is actuated by a spring 14 which tends to turn said arm 13 in clock-wise direction in the drawing. Said

arm 13 is adapted to be actuated from outside the lock by means of a key or handle in any suitable well-known manner. For opening the lock the arm 13 is turned to the left 5 or in counter-clockwise direction in the drawing against the action of the spring 14. When the lock is locked and the latch-bolt 1 occupies its maximum extended position, as illustrated in Fig. 1, a stud or projection 10 15 on the arm 13 is in a longitudinal slot 16 in the plate 8. During said counter-clockwise turning of the arm 13 said stud 15 will strike against the rear end of said slot which forms a stop or abutment 17 for the stud 15. 15 The said turning of the arm 13 will thus obviously result in the plate 8 and thus also the latch-bolt 1 being moved inwards in the lock casing 3 while compressing the spring 12. When the arm 13 has been turned 20 through a certain angle the stud 15 will move out of engagement with the abutment 17 and drop into the transverse slot or groove 18 in the plate 8. During the continued turning of the arm 13 the stud 15 25 will engage the edge 19 of said slot 18 and move downwards in said slot, until the latch-bolt 1 has become fully retracted within the lock and the parts have arrived in the positions shown in Fig. 2. The lock is now 30 opened.

If the key or handle by means of which the arm 13 is actuated, is now released the spring 12 will of course push the plate 8 and the latch-bolt 1 outwards, and the 35 spring 14 will turn the arm 13 in clock-wise direction. During the first period of the movements of these parts the stud 15 will of course move between the edges 19 and 20 of the slot 18 upwards in said slot, until the 40 stud 15 strikes the upper edge or border 21 of said slot, which edge 21 forms an abutment for the stud 15 with which said stud engages. The plate 8 with the latch-bolt 1 and the arm 13 will therefore stop in the 45 positions shown in Fig. 3, in which the stud 15 bears against the edge 21 and the edge 19. The parts are so dimensioned that in this position only the beveled portion of the latch-bolt 1 projects outside the lock. With 50 the parts in this position it is therefore possible to slam shut the door, drawer or lid into which or in which the lock is secured. The purpose of the slot 18 is to ensure that during the said outward movement of the 55 parts the stud 15 shall be sure to engage the abutment 21. If the forward edge 20 of the slot 18 did not guide the stud 15 to move upwards against the said abutment 21, and if the spring 14 was very stiff it might happen that when the key or handle is released, 60 the arm 13 is turned so rapidly by its spring 14 that it moves the stud 15 out of engagement with the edge 19 and past the abutment 21 out into the longitudinal slot 16 approximately to the position shown in Fig. 65

1, whereby the plate 8 and the latch-bolt 1 would also be free to resume, actuated by the spring 12, the position shown in Fig. 1 in which the latch-bolt 1 projects fully outside the casing. It would then be 70

When the parts of the lock occupy the positions shown in Fig. 3, and the door or drawer is pushed shut, owing to the engagement of the beveled portion of the latch-bolt 75 1 with the door-post or the like the latch-bolt will be pushed back into the lock casing together with the plate 8, which compresses the spring 12. During this movement of the plate 8 the abutment or edge 21 will of course slide in its own direction away from the stud 15 which becomes released, after which the arm 13 will be turned by its spring 14 outwards approximately to the position shown in Fig. 1. When the door 80 has been shut there is thus no longer anything to prevent the plate 8 and the latch-bolt 1 from being moved outwards by the spring 12 until said parts resume the positions shown in Fig. 1, in which the flanges 90 9 on the plate 8 bear against the lugs 11 in the lock casing. The described clock-wise turning movement of the arm 13 is limited by a stud 22 which is secured in the lock casing and projects through a slot 23 in the 95 arm 13 and also passes through a slot 24 in the plate 8, the ends of said slot 24 serving by engaging said stud 22 to limit the movements of the plate 8 and the latch-bolt 1 in both directions. 100

The parts have now resumed the positions shown in Fig. 1. The latch-bolt 1 is secured against being forced from the outside inwards into the lock by a lug 25 on the plate 8 being located opposite a portion 26 of the 105 arm 13. If an attempt is made to open the lock by forcing the latch-bolt inwards, the lug 25 will be forced against the portion 26, and the point of engagement between said two parts being somewhat below the axis of 110 rotation of the arm 13 in Fig. 1, the engagement of said two parts will only tend to turn the arm 13 to the right in Fig. 1, which turning movement is prevented, however, by the stud 22. In this manner the 115 latch-bolt is thus securely prevented from being forced inwards in the lock. As shown in Fig. 1 there is a sufficient play between the stud 15 on the arm 13 and the abutment 17 on the plate 8 for enabling said arm 120 13 to be turned, when the lock is being opened by means of its key or handle, through such an angle that the portion 26 is raised above the lug 25 before the stud 15 engages the abutment 17 and the plate 8 125 and the latch-bolt 1 begin their inward movement.

In the embodiment illustrated, which represents a door lock, it is possible further to secure the latch-bolt against being forced 130

inwards and also to prevent the lock from being opened from the outside with a key, by means of the catch 27 which may be moved by means of a catch knob 28 secured 5 to the catch and projecting on the outside of the lock. The neck 29 of said knob is movable in a slot 30 in the lock casing which slot is provided with two recesses and an intermediate projection, as shown in Fig. 4. 10 The catch 27 is pressed against the lock casing by means of a spring 32 inserted between the catch and the head of a stud 31 secured to the lock casing, so that the neck 29 will thus be pressed into one of the recesses in the slot 30. When the catch 27 is moved upwards by means of the knob 28 the neck 29 slides over the projection in the slot 30 into the upper recess in Fig. 4, so 15 that the catch 27 arrives in the position 20 shown with dotted and dashed lines in Fig. 1, and the catch will thus be positioned behind the head 5 of the rod 4, and will prevent the latch-bolt 1 from moving inwards in the lock, so that the lock can not 25 be opened by means of its key or handle, nor by applying pressure to the latch-bolt from the outside. As shown with dotted and dashed lines in Fig. 2, it is also possible by means of the catch 27 to secure the 30 latch bolt in its maximum retracted position within the lock, which will thus remain opened.

It will be understood that the invention is not limited to the embodiment described 35 and illustrated in the drawing. It is not necessary, for instance, that the latch-bolt be loose and removable from the plate 8, as these two parts may be made integral, although the construction described is particularly suitable in respect of door locks 40 for making such locks easily adaptable for doors opening outwards or for doors opening inwards. In the embodiment illustrated the arm 13 is intended to be actuated in a similar manner as in the well known cylinder locks, but said arm may of course be 45 actuated in any other suitable manner, particularly when the lock is intended for drawers, cabinets or the like.

50 I claim:

1. A lock of the type described comprising a bolt capable of assuming a maximum retracted, intermediate and a maximum extended position, a bolt-actuating arm cooperating with said bolt to retract the same and to retain said bolt in a position intermediate its maximum retracted position and its maximum extended position, and means for retaining said arm in positive engagement with said bolt to insure synchronous movement of said members during the movement of said bolt from its maximum retracted position to said intermediate position.

65 2. A lock of the type described comprising

ing a bolt capable of assuming a maximum retracted, intermediate and a maximum extended position, a bolt-actuating arm cooperating with said bolt to retract the same and to retain said bolt in a position intermediate its maximum retracted position and its maximum extended position, a stud on one of said parts, and a guide slot for said stud in the other of said parts, said guide slot being adapted to retain and guide 70 said stud during the movement of said bolt from its maximum retracted position to said intermediate position.

3. A lock of the type described comprising a casing, a bolt capable of assuming a maximum retracted, intermediate and a maximum extended position and slideable longitudinally in said casing, said bolt having a transverse slot and an abutment at one end of said slot, a rotatable bolt-actuating arm in said casing adapted to cooperate with said bolt to retract the same within said casing, and a stud on said arm adapted to be guided and retained in said slot during the outward movement of said bolt from its maximum retracted position and by engagement with said abutment to retain said bolt in a position intermediate its maximum retracted position and its maximum extended position.

4. A lock of the type described comprising a casing, a bolt capable of assuming a maximum retracted, intermediate and a maximum extended position and slideable longitudinally in said casing, said bolt having a transverse slot and an abutment at one end of said slot, a rotatable bolt-actuating arm in said casing adapted to cooperate with said bolt to retract the same within said casing, a stud on said arm adapted to be guided and retained in said slot during the outward movement of said bolt from its maximum retracted position and by engagement with said abutment to retain said bolt in a position intermediate its maximum retracted position and its maximum extended position, a lug on said bolt, and a projection on said arm adapted to occupy a position in the path of said lug when the bolt is in its maximum extended position.

5. A lock of the type described comprising a casing, a bolt capable of assuming a maximum retracted, intermediate and a maximum extended position and slideable longitudinally in said casing, said bolt having a transverse slot and an abutment at one end of said slot, a guide rod for said bolt, a rotatable bolt-actuating arm in said casing adapted to cooperate with said bolt to retract the same within said casing, a stud on said arm adapted to be guided and retained in said slot during the outward movement of said bolt from its maximum retracted position and by engagement with 120

125

130

said abutment to retain said bolt in a position intermediate its maximum retracted position and its maximum extended position, a lug on said bolt, and a projection 5 on said arm adapted to occupy a position in the path of said lug when the bolt is in its maximum extended position.

6. A lock of the type described comprising a bolt capable of assuming a maximum

retracted, an intermediate and a maximum 10 extended position, an arm, one of said members having a slot, the other of said members having a stud guided by said slot during the movement of said bolt from maximum retracted position to the intermediate 15 position and adapted to retain said bolt in said last named position.

JOHAN WALDEMAR LINDBERG.
